(57) **CLAIM**

The ornamental design for a cookware handle, as shown and described.

DESCRIPTION

FIG. 1 is a right side elevational view of a cookware handle showing my new design;

FIG. 2 is a top plan view of the cookware handle of FIG. 1; FIG. 3 is a bottom plan view of the cookware handle of FIG. 1; and,

FIG. 4 is a bottom left perspective view of the cookware handle of FIG. 1.

The broken line showings in FIGS. 1-4 are for illustrative purposes only, depicting the environment of the new design, forming no part thereof as claimed.

1 Claim, 4 Drawing SheetsFIG. 1

FIG. 2

FIG. 3

FIG. 4
